UNITED STATES PATENT OFFICE.

JOSEPH H. NIÉSEN, OF GRAFTON, WISCONSIN.

WASHING MACHINE.

Application filed March 16, 1925. Serial No. 15,896.

This invention relates to washing machines.

Objects of this invention are to provide a washing machine in which all of the mechanism is positioned below the clothes, and the clothes never come in contact with the moving portions of the machine, but are completely protected from any damage whatsoever from these parts.

Further objects are to provide a washing machine which is of extremely simple and strong construction, and may be very cheaply manufactured, and which, although of simple construction, nevertheless effectively circulates the water through the clothes in different directions to thus insure complete and thorough cleaning of the clothes in a minimum period of time.

An embodiment of the invention is shown in the accompanying drawings, in which the single figure is a vertical sectional view through the machine.

Referring to the drawings, it will be seen that the machine comprises a main compartment 1 provided with a removable cover and adapted to receive the clothes. This compartment is provided with a downwardly extending cylindrical portion or slightly conical portion 2 which freely opens into the bottom of the compartment 1.

A perforated plate or screen 3 is removably positioned in the bottom of the compartment 1 and thus supports and retains the clothes in such compartment although freely permitting circulation of water.

It is to be noted from reference to the drawing that the compartment 2 is provided with an inner cylinder 4 which is spaced therefrom to provide an annular channel 5 between the cylinder 4 and the wall of the compartment 2.

A piston 7 fits within the cylinder 4 and is adapted to be freely reciprocated therein. This piston is carried by a rod 8 and such piston rod is in turn connected by means of a pitman 9 with a crank 10. The crank, it will be noted, is provided with bearings 11 on opposite sides thereof, and is rigidly connected with a worm wheel 13 driven by a worm 14, such worm being driven from a motor or other suitable source of power.

It is to be noted also that the piston 8 passes through a stuffing box 15 to prevent leakage of the water downwardly from the machine.

Further, it will be noted that the inner

cylinder 4 has its bottom spaced upwardly from the bottom of the compartment 2 for a purpose hereinafter to appear.

The entire apparatus is carried by a portable frame consisting of a bottom 16 upon which the bearings 11 and 12 are rigidly secured, and uprights 17 which support the compartment 1, suitable rollers being provided to facilitate movement of the ma- 65 chine.

The operation of the apparatus is as follows:—Water is poured into the machine until it partly fills the compartment 1. Clothes are placed in this compartment and the cover closed down and the machine started. As the piston 7 is reciprocated, the water is drawn first inwardly down the annular channel 5, and into the lower end of the cylinder 4 on the upstroke of the piston, as shown in full lines by the arrow in the figures. The water is also forced upwardly through the perforated screen 3 and through the clothes. Upon down stroke of the piston, the water is forced in a reverse direction from the lower end of the cylinder 4 upwardly through the annular passage 5 through the screen and through the clothes, as shown by the dotted arrows in the figure. The water also passes downwardly through the clothes into the upper end of the cylinder 4.

It will be seen, therefore, that a very simple and strong type of washing machine has been provided which is effective in operation, and in which the clothes are completely protected from possible damage by the moving parts.

Although the invention has been described in considerable detail, it is to be understood that the invention may be variously embodied and is, therefore, to be limited only as claimed.

I claim:

1. A washing machine comprising a main compartment adapted to receive clothes, a stationary screen positioned in the lower portion of said compartment and adapted to support the clothes, a downwardly extending auxiliary compartment communicating with said main compartment, a vertical cylinder carried within said auxiliary compartment and spaced from the bottom and side walls thereof and having its top adjacent said screen, a piston slidably mounted within said cylinder, and means for reciprocating said piston.

2. A washing machine comprising a main

compartment adapted to receive clothes, a screen positioned in the lower portion of said compartment and adapted to support the clothes, a downwardly extending auxiliary compartment communicating with said main compartment, a vertical cylinder carried within said auxiliary compartment and spaced from the bottom and side walls thereof and having its top adjacent said screen, a piston slidably mounted within said cylinder, a piston rod rigidly secured to said piston and projecting through the lower wall of said auxiliary compartment, and power driven means positioned below said auxiliary compartment and connected to said rod for reciprocating said piston. In testimony that I claim the foregoing I have hereunto set my hand at Milwaukee, in the county of Milwaukee and State of Wisconsin.

JOSEPH H. NIESEN.
